UNITED STATES PATENT OFFICE

HUGH L. GADDIS, OF CLEVELAND, OHIO, ASSIGNOR TO GLOBE MACHINE & STAMPING COMPANY, OF CLEVELAND, OHIO, A CORPORATION OF OHIO

INSERT FOR CONCRETE

Application filed January 23, 1928. Serial No. 248,602.

This invention relates to inserts for concrete and particularly to devices of that nature intended for supporting a pipe hanger or other suspension device, from the ceiling 5 of a room.

It is one of the objects of the invention to provide an insert that may be made from sheet metal at a minimum cost and which will be securely held in concrete and also 10 adapted for convenient application and so formed that the concrete will readily flow into all parts of the device that are intended for the reception of the concrete.

Other objects of the invention and the features of novelty will be apparent from the following description taken in connection with the accompanying drawings, of which—

Fig. 1 is a perspective view of an insert made in accordance with my invention; 20 Fig. 2 is a transverse section through the insert illustrated in Fig. 1 and showing the arrangement of the concrete thereon as well as the position of a pipe hanger therein; and Fig. 3 is a central longitudinal section of 25 the insert shown in Fig. 1.

Referring to the drawings, 10 indicates the main body portion of the insert which is provided with upright side walls 11 and 12 and a bottom wall 13. The body portion 10 is made from sheet metal and the upper portions of the side walls are bent inwardly as shown at 14 and then outwardly as shown at 15 to form means for securely bonding the insert to the concrete. The bottom wall 13 is provided with a slot 16 through which a nut 17 or other supporting device may be inserted and, ordinarily, a hanger bolt 18 will be secured to the nut 17, or its equivalent.

An inverted U-shaped member 19 is arranged within the body portion 10 with its longitudinal edges in engagement with the inner surfaces of the side walls thereof, so as to form a pocket 20 for the nut 17, from which the concrete will be excluded. The lower 40 edges of the end walls of the member 19 have outwardly projecting flanges 20' which are preferably spot-welded to the upper surface of the bottom wall 13 to thereby secure the parts together. The bottom wall 13 is preferably provided with perforations 21, adja-

cent its ends, through which nails or wires may pass for the purpose of securing the insert to the concrete forms, prior to the pouring of the concrete. The upper portions of the side walls 11 and 12 are preferably provided with elongated openings or slots 22 through which the concrete may pass, for the purpose of bonding the concrete, on opposite sides of the side walls and also to provide means for better securing the insert to the concrete. 55

The insert 19 may be made of a strip of sheet metal, of lighter gauge than the body portion 10, as the only purpose of the member 19 is to provide an open space within the insert and also to brace the side walls against the pressure of the concrete on the outer sides thereof. 60

While I have illustrated and described what I now consider to be the preferred form 70 of my invention, it will be understood that some changes may be made in the details of construction without departing from the spirit of the invention as it is defined in the appended claim. 75

Having thus described my invention what I claim is:

An insert for concrete consisting of a sheet metal body having bottom and side walls and open ends, said bottom wall having an opening therein through which a nut may be inserted, and an inverted U-shaped sheet-metal member arranged between said side walls with its longitudinal edges in engagement therewith and with its vertical sides spaced inwardly from the ends of the walls of said body, said vertical sides having outwardly bent flanges secured to the inner face of said bottom wall and lying wholly within the spaces between said vertical sides and the ends of the walls of said body. 85

In testimony whereof, I hereunto affix my signature.

HUGH L. GADDIS.
